APPARATUS FOR GRADING MATERIAL

Damon D. Dunkin, Guion, Ark.

Application March 30, 1929. Serial No. 351,208

5 Claims. (Cl. 209—120)

The present invention relates to an improved method and apparatus for grading materials and is designed primarily for the grading of relatively fine material, such for example as sand, although it is not necessarily restricted to such use.

An important object of the invention is to provide apparatus wherein the sand or other material to be graded may be quickly and efficiently separated into a plurality of different grades, each grade containing grains of a relatively predetermined size.

Another object of the invention is to provide such apparatus wherein the sand or other material to be graded is deposited upon a traveling surface moving in a circular path, the movement of said surface being such that a plurality of different relatively predetermined grades of material will be successively discharged therefrom at spaced points or intervals in its travel.

Another object of the invention is to provide such apparatus wherein the sand or other material to be graded is discharged, in a mixed product, onto a drum rotatable preferably about a substantially horizontal axis, said drum being adapted, upon rotation thereof, to effect the separation of a plurality of different grades of material from the mixed product, each grade containing grains of a relatively predetermined size.

A further object of the invention is the provision of means for receiving the coarse grade of material separated from the mixed product and directing the same to a desired location, said means being adjustable to vary the grain size of the coarse grade of material.

Still another object of the invention is the provision of means for receiving a portion of the material separated from the mixed product and effecting a further separation thereof to produce the second and third grades, said means being adjustable to maintain the second grade practically constant.

Other objects and advantages of the invention will become more apparent during the course of the following description when taken in connection with the accompanying drawings.

In the drawings forming a part of this application and wherein like numerals are employed to designate like parts throughout the same,

Fig. 1 is a front elevation, partially broken away, of grading apparatus provided by the present invention.

Fig. 2 is a vertical transverse section taken substantially on line 2—2 of Fig. 1.

Fig. 3 is an enlarged detail sectional view of the lower portion of the feed hopper, and

Fig. 4 is a detail elevation showing the driving means for the cleaning brush.

Referring now more in detail to the accompanying drawings, the numeral 10 designates in its entirety a suitable supporting framework of any conventional or preferred construction and which is adapted to support the various parts of the grading apparatus or machine as will be more clearly hereinafter apparent. Carried by the supporting framework, and more particularly by the spaced horizontal beams 11 and 12, are aligned bearings 13 and 14 within which is journaled the horizontal shaft 15 having mounted thereupon the drum 16. The drum 16 is preferably composed of a plurality of spaced metallic spiders 17 carrying the wooden cylinder or lagging 18 to which is secured the covering 19 of canvas or any other suitable material. The drum 16 is adapted to rotate in the direction indicated by the arrow in Fig. 1 and may be driven by means of a pulley 20 keyed to one end of shaft 15 and about which is trained a belt 21.

Mounted above the drum 16, upon the spaced horizontal beams 22 and 23 of the supporting framework 10, is the feed hopper or box 24 provided with an outlet slot 25 in the bottom thereof which extends substantially the entire length of the drum so that the sand or other material to be graded will be discharged onto the drum in the form of a ribbon. The feed hopper is preferably so positioned that the material will be fed onto the drum just back of the vertical center thereof. Carried by the feed hopper and positioned beneath the outlet slot 25 are the horizontally spaced rollers 26 and 27 journaled at their opposite ends in bearing blocks 28 mounted for horizontal sliding movement within guideways 29. The feed rollers may be adjusted toward and away from one another by means of the hand wheels 30 to vary the space therebetween. While the rollers are ordinarily maintained stationary during the feeding of the material therebetween, either one or both of them may be rotated by means of hand wheel 31 carried by the shaft thereof. Thus, in case of obstructions between the rollers, such as may be caused by sticks and the like, a turn of one or both rollers will serve to remove this obstruction and free the material.

Arranged beneath the drum 16 and extending throughout the length thereof is a relatively large bin or receptacle divided into a plurality of individual compartments or catch boxes 32, 33, 105 arranged transversely of the drum. The bins 32, 33, 110

34, 35 and 36. These compartments, which are of varying sizes, may be provided with outlet spouts or the like 37 to 41 respectively for conveying the material therefrom to any desired 5 location. The individual compartments 32 to 36 inclusive are formed by the provision of spaced vertical partition walls 42, 43, 44 and 45. The partition walls 42, 43 and 44 are of substantially the same height while the partition wall 45 is 10 shown as being considerably higher and, in fact, projecting upwardly almost to the drum 16.

In carrying the present invention into practice, the sand or other material to be graded is adapted to be fed from the feed hopper 24 onto the 15 rotating drum 16 which, upon rotation, is adapted to effect the separation of a plurality of different grades of material, each grade containing grains of a relatively predetermined size. In other words, upon rotation of the drum, a plurality of different relatively predetermined 20 grades of material will be successively discharged therefrom at spaced points or intervals in its travel. The coarser grains will naturally be first thrown or discharged from the drum by the 25 centrifugal force created thereby and then the progressively finer grains. While the size of the drum and also the speed of rotation thereof may be varied, dependent upon the character of the sand or other material to be graded, it has been 30 found that a drum thirty inches in diameter and rotating at a speed of thirty revolutions per minute operates very satisfactorily. The speed of rotation of the drum is an important factor. A too high rate of speed gives a throwing 35 action which causes the discharge of too much dust and fine grains of material with the coarser grains while too slow a speed fails to keep the mass of material agitated and alive. With correct speed, the material is properly agitated and kept alive so as to allow the fine grains 40 to sink through the coarser grains and become enmeshed in the fabric covering of the drum, while, at the same time, the larger or coarser grains work through and to the top of the mass. 45 Upon rotation of the drum 16, there is a constant movement of the grains of material thereon and the coarser grains working to the top will be the first discharged therefrom by the centrifugal force created thereby. The coarser 50 grains initially thrown from the drum are designated 46 and this material is caught upon an inclined deflector plate 47 and directed thereby into the first compartment or catch box 32 forming the first finished grade or product. The deflector plate is pivotally mounted so that the upper end thereof may be swung upwardly and outwardly or downwardly and inwardly to vary 55 and control the grain sizes in the coarser grade of material. That is, by moving the deflector plate to the right so as to lower the upper end thereof and bring it closer to the drum, a somewhat finer grade of material will be caught thereby whereas, on the other hand, if the plate be moved to the left to raise the upper end, only the coarser grains of material or those thrown 60 furtherest outwardly by the drum will be caught thereby.

The deflector plate 47 is carried by a shaft 48 70 rotatably supported at its opposite ends by the vertical legs 49 and 50 of the supporting framework 10. Secured to the underside of the deflector plate, adjacent each end thereof, is a segment 51 provided with gear teeth 52. Also carried by the supporting framework 10 and positioned in line with shaft 48 is a second shaft 75

53 having keyed thereto gears 54 meshing with the teeth on segments 51 so that upon turning of shaft 53, the gears 54 will be rotated to effect a swinging or rocking movement of the deflector plate about the shaft 48. To effect the desired rotation of shaft 53, there may be keyed to one end thereof a worm gear 55 driven from a worm (not shown) but operable by a hand wheel 56. Thus, upon rotation of hand wheel 56 the deflector plate may be moved to assume the desired angle with respect to drum 16. 80

The relatively finer material next discharged from the drum is indicated at 57 and falls downwardly onto the horizontal platform or regulator plate 58 provided with the upstanding end walls 59. The material 57 is allowed to pile up on the regulator plate as at 60 and when the pile is built up to the angle of slide, the material 57 falling from the drum will be further separated, a portion thereof being directed into the compartment 33 and a portion into compartment 34. The material 61 received within compartment 33 forms the second finished grade or product while the material 62 received within compartment 34 90 constitutes the third grade. There is also mixed with the third grade of material 62 those relatively finer grains 57' discharged from the drum directly into compartment 34. 95

According to this invention, the third grade of material 62 is preferably returned to the machine for regrading, this being desirable since it ordinarily contains some material that belongs in the second grade and also an excess of fine material. The original sand fed to the grader will vary according to the location from which 105 obtained and therefore, the regulator plate 58 is preferably movable horizontally so that as the sand varies, the position of said plate may be correspondingly adjusted to keep the second grade of a constant nature and throw any variation into the third grade. Naturally, if the second grade be kept of a constant nature the third grade will vary both in amount and character of the grains. The attempt is made to have the second grade a constant product and upon proper 110 positioning of the regulator plate, the second grade can be kept practically constant and the variation thrown into the third grade. The third grade not being constant is returned to the machine for regrading. If it is found that the sand 115 grains change in the feed and the second grade shows too many fine grains, the regulator plate is moved to the left so that more of the material 57 falls into compartment 34 while, on the other hand, if the sand is coarser, then the regulator plate is moved to the right so that more of the material 120 will fall into compartment 33. 125

The regulator plate 58 may be supported at its opposite ends upon wheels 63 mounted upon rails 64 carried by the supporting framework 10. Secured to the bottom of the regulator plate adjacent each end thereof is a rack bar 65 engageable by a gear 66 keyed to shaft 67, said shaft being operable by a hand wheel or the like 68. Upon rotation of shaft 67 and gears 66, regulator plate 58 may be moved horizontally to the left or right as desired. By properly controlling the position of this plate, the amount of fine material going into the second grade can be controlled to very close limits. 135

The still finer grains of material indicated at 69 are next discharged from the drum and are received within the compartment 35 forming the fourth grade or product while the very finest 140 grains or dust adhering to the fabric covering 145

of the drum may be removed therefrom by means of the rotatable brush 70, this dust being designated 71 and received within compartment 36. The brush 70 is preferably mounted upon a shaft 72 carrying at one end thereof a sprocket 73 about which is trained sprocket chain 74 to effect the desired rotation of said brush.

It is to be understood that the form of the invention herewith shown and described is to be taken as the preferred embodiment of the same, and that various changes in the shape, size and arrangement of parts may be resorted to without departing from the spirit of the invention or the scope of the subjoined claims.

15 I claim:

1. In apparatus for grading sand and like materials, a drum for receiving the material to be graded thereon, means for rotating the drum about a substantially horizontal axis to effect the successive discharge therefrom of a plurality of different grades of material, each containing grains of a relatively predetermined size, a horizontally disposed platform for receiving a portion of the material discharged from the drum 25 and effecting a further separation thereof to produce the second and third grades, and means for moving said platform horizontally to control the amount of material passing into the said second and third grades.

30 2. In apparatus for grading sand and like materials, means for receiving the material to be graded, means for rotating the first named means in a circular path about a substantially horizontal axis to effect the successive discharge 35 therefrom of a plurality of different grades of material, each containing grains of a relatively predetermined size, horizontally disposed means for receiving a portion of the material discharged from the first mentioned means and effecting a further separation thereof to produce the second and third grades, and means for moving said last named means horizontally to control the amount of material passing into the said 40 second and third grades.

45 3. In apparatus for grading sand and like materials, a drum for receiving the material to be graded thereon, means for rotating the drum about a substantially horizontal axis to effect the successive discharge therefrom of a plurality of 50 different grades of material, each containing grains of a relatively predetermined size, means

for receiving a portion of the material discharged from the drum and effecting a further separation thereof to produce the second and third grades, and means for moving said last mentioned means horizontally to control the amount of material passing into the second and third grades.

5 4. In apparatus for grading sand and like materials, means for receiving the material to be graded, means for rotating the first named means in a circular path about a substantially horizontal axis to effect the successive discharge therefrom of a plurality of different grades of material, each containing grains of a relatively predetermined size, a deflector plate mounted in proximity to the first mentioned means for receiving the coarse grade of material discharged therefrom and directing it to a desired location, means for adjusting the deflector plate to vary the grain size of the coarse grade of material, horizontally disposed means for receiving a portion of the material discharged from the first mentioned means and effecting a further separation thereof to produce the second and third grades, and means for moving said last named means horizontally to control the amount of material passing into said second and third grades.

10 5. In apparatus for grading sand and like materials, a drum for receiving the material to be graded thereon, means for rotating the drum about a substantially horizontal axis to effect the successive discharge therefrom of a plurality of different grades of material, each containing grains of a relatively predetermined size, an inclined deflector plate mounted in proximity to the first mentioned means for receiving the coarse grade of material discharged therefrom and directing it to a desired location, means for rocking the deflector plate to move it closer to or further away from said drum whereby to vary the grain sizes of the coarse grade of material, means for receiving a portion of the material discharged from the drum and effecting a further separation thereof to produce the second and third grades, and means for moving said last mentioned means horizontally to control the amount of material passing into the second and third grades.
